(57) **CLAIM**

The ornamental design for a docking station for a robot, as shown and described.

DESCRIPTION

FIG. 1 is perspective view of the docking station for a robot showing our new design with a robot;

FIG. 2 is a perspective view of the docking station for a robot showing our new design by itself;

FIG. 3 is a front view thereof;

FIG. 4 is right side view thereof;

FIG. 5 is a top view thereof;

FIG. 6 is a rear view thereof;

FIG. 7 is a left side view thereof; and,

FIG. 8 is bottom view thereof.

The broken lines in the drawings depict unclaimed environmental subject matter.

1 Claim, 4 Drawing Sheets
